CRUSHER FOR AUTOMOBILE ENGINES
Walter R. Emert, P.O. Box 222, Hatfield, Pa.
Filed Mar. 24, 1961, Ser. No. 98,217
4 Claims. (Cl. 241—268)

The present invention generally relates to a crusher and more particularly to such a crusher specifically adapted for use in crushing relatively large objects such as automobile engines and the like.

As is well known in the scrap metal industry, it is desirable to separate the different types of metal in order to eliminate certain impurities and undesirable metals. An automobile engine is a prime source of certain types of scrap metal such as cast iron and it is desirable to separate the cast iron of the automobile engine block from the other components which are not constructed of cast iron such as the crankshaft. It is quite time consuming to manually remove the crankshaft and its attached connecting rods and the like since it requires the removal of a considerable number of bolts. Therefore, it is the primary object of the present invention to provide a crusher capable of receiving automobile engine blocks and crushing these blocks in such a manner that the cast iron will be stripped from the crankshaft and the like so that the two different types of metals may be easily separated from each other thereby providing a more effective classification and separation of the different scrap metals.

In carrying out the purposes of the invention, this invention provides a crusher of the type having cooperating jaws of which at least one jaw is movable relative to the other on a generally horizontal axis extending transversely to the direction of the jaw movement. The jaws cooperate to provide a crushing space therebetween in which the crushing space is downwardly tapered and the movable jaw is pivoted about a stationary axis adjacent the entrance end of the crushing space. The jaw structures of the crusher are constructed in such a manner to prevent the automobile engines from riding upwardly in the crushing space when the swing jaw moves towards the stationary jaw and also the structure which prevents upward movement of the automobile engines also permits easier discharge of the crushed material from the bottom end of the jaws.

Another important object of the present invention is to provide a crusher construction in accordance with the preceding object that is simple in construction, highly effective for its particular purposes and generally inexpensive to construct, operate and maintain.

These together with other objects and advantages which will become subsequently apparent reside in the details of construction and operation as more fully hereinafter described and claimed, reference being had to the accompanying drawings forming a part hereof, wherein like numerals refer to like parts throughout, and in which:

FIGURE 1 is a top plan view of the crusher of the present invention;

FIGURE 2 is a longitudinal, sectional view taken substantially upon a plane passing along a section line passing through the center of the crusher;

FIGURE 3 is a front view of the stationary jaw of the crusher;

FIGURE 4 is a front view of the movable or swing jaw of the crusher; and

FIGURE 5 is a transverse, sectional view taken substantially upon a plane passing along section line 5—5 of FIGURE 3 illustrating the details of construction of the jaw.

Referring now specifically to the drawings, the numeral 10 generally designates the crusher which includes any

2

suitable type of frame 12 having a drive shaft 14 journaled thereon by bearings 16. The drive shaft 14 is provided with a centrally disposed eccentric 18 and one end of the shaft 14 is provided with a flywheel 20 and the other end of the shaft is provided with a power pulley 22 receiving a belt 24 driven by a suitable motor 26 which may be an electric motor or internal combustion engine provided with a suitable governor for controlling the rotational speed thereof.

10 Mounted on the frame 12 is a stationary jaw generally designated by numeral 28 and a movable or swing jaw generally designated by the numeral 30 which is supported for oscillation about a transverse shaft 32 mounted on the frame 12 by suitable bearings 34.

15 A mechanism is provided for oscillating the swing jaw 30 which includes a pitman cap 36 of any suitable split construction to which is attached a pair of downwardly extending and converging pitman rods 38 which are interconnected at their bottom ends by straps 40. Also,

20 the bottom ends of the pitman rods 38 are provided with generally spherical shaped enlargements 42 which are actually in the form of pitman rod nuts. The pitman rod nuts 42 are received in sockets in a pitman rocker 44 which engages the rear end portion of a front toggle 46.

25 The front toggle 46 is connected with the rear of the swing jaw 30 by a front toggle seat 48. The rear end of the front toggle 46 is provided with a seat 50 receiving the forward end of a rear toggle 52 attached to a rear toggle seat 54. The rear toggle seat 54 is connected to a

30 toggle block 56 which engages part of the frame and is held in place by a toggle block retainer 58. The shaft, pitman cap, eccentric, pitman rods and toggle assembly are similar to that employed in a presently available crusher manufactured by Trayler Engineering and Manufacturing

35 Co., of Allentown, Pa., and this construction also includes a tension rod 60 pivotally connected to the swing jaw by a tension rod bolt 62 and being spring biased for urging the swing jaw away from the stationary jaw by virtue of a tension rod spring 64. The swing jaw and stationary jaw both are of hollow construction and include suitable means for removal of and replacement of the crushing jaws.

40 Also, the toggle 46 is provided with a jack spring assembly 66 for retaining the rear end of the toggle 46 against the toggle block 44.

45 The essence of the present invention resides in the specific jaw plate structure including the stationary jaw face or plate structure designated by numeral 68 and the swing jaw face or plate structure designated by numeral 70. The stationary jaw plate structure 68 includes an enlarged plate 72 having a plurality of longitudinally extending ribs or projections 74 thereon which extend from end to end and taper in thickness from the bottom edge upwardly in the manner illustrated in FIGURES 2

50 and 5 with the thicker portion being adjacent the top although the thicker portion is beveled outwardly as at 76. Also, the spacing between the projecting ribs or bars tapers from the bottom to the top with the distance between the bars being greater at the bottom than at the

55 top which provides somewhat of a V-shaped bar or rib construction which serves as a lock or holdown to keep the vehicle engines from riding up when the swinging jaw comes forward into a crushing position. While the dimensions may be varied, representative dimensions which have been successfully employed are as follows. The plate 72 is 36 inches wide and 48 inches high and this plate may slope outwardly slightly at a slight angle to permit the motor to be fed down at the top of the jaws to a crushing position. The plate is preferably 4

60 inches thick and the bars or ribs 74 are 2½ inches wide and the bars 74 have a maximum height of 5 inches at a point where the outward flare 76 starts and they taper

downwardly to approximately $2\frac{3}{4}$ inches in height at the bottom. The spacing between the bars 74 is 3 inches at the bottom and tapers upwardly to $2\frac{1}{2}$ inches at the top as illustrated in FIGURE 3. The outward flare portion 76 may extend down approximately 12 inches to provide somewhat of a throat or entrance to the jaws so that the engine may reach a crushing position. The upward convergence of the bars 74 together with the inclined surface formed by the increase in depth from $2\frac{3}{4}$ inches at the bottom to 5 inches adjacent the top provides a 10 holdown for the vehicle engine to prevent the engine from riding upwardly against the stationary jaw when the swing jaw moves to a crushing position.

The swing jaw plate 70 includes an enlarged backing plate 78 with a plurality of ribs or bars 80 mounted thereon. The plate 78 may be 2 inches thick, 76 inches in length and 36 inches wide. The bars 80 are 3 inches thick and welded onto the 2 inch thick plate 78. The bars 80 start adjacent the bottom with a height of 5 inches and taper down to a height of 3 inches adjacent the top. The 15 bottom ends of the bars are flared outwardly as at 82 for facilitating discharge of crushed material. Also, the bars 80 are spaced apart 3 inches at the top and diverge downwardly and are spaced apart approximately 3 $\frac{1}{2}$ inches at the bottom thus allowing the crushed cast 20 metal to drop between the bottom of the jaw assemblies onto an off-bearing conveyor assembly generally designated by numeral 84 and which may be of any conventional construction.

In employing the dimensions, a movement of $1\frac{1}{2}$ inches of the crushing jaw was obtained by providing an eccentric having sufficient eccentricity to provide the crushing jaw with a $1\frac{1}{2}$ inch compression stroke. This was necessary in order to get sufficient crushing throw on the swing jaw inasmuch as cast iron will bend slightly before it actually breaks. Also, the crushing jaw is in a nearly vertical position when engaged by an automobile engine thus further preventing upward riding movement of the vehicle engine.

In actual practice, a relatively large number of automotive vehicle engines, including the block and crankshaft assembly have been dropped into the crusher in a given time and these engines have been effectively crushed and the crankshaft assemblies have been effectively separated from the cast iron block and related housings. This greatly facilitates the reduction of the scrap metal into its proper classifications and eliminates considerable impurities that would be present if the cast iron was not separated from the other metals.

The foregoing is considered as illustrative only of the 50

principles of the invention. Further, since numerous modifications and changes will readily occur to those skilled in the art, it is not desired to limit the invention to the exact construction and operation shown and described, and accordingly all suitable modifications and equivalents may be resorted to, falling within the scope of the invention as claimed.

What is claimed as new is as follows:

1. A material crusher comprising, in combination, a pair of generally upstanding coating stationary and pivoted jaws for receiving material to be crushed therebetween, said jaws including opposed faces comprising plates and further comprising spaced, vertical, staggered ribs of uniform width from end to end on said plates and coextensive therewith, said ribs being downwardly divergent and defining, in conjunction with the plates, a plurality of gradually, continuously and uniformly, upwardly tapered, open-end, grooves for the discharge by gravity of crushed material from between the jaws.

2. A material crusher in accordance with claim 1, the ribs on one of the plates progressively increasing in height toward their upper ends and terminating in reversely beveled upper end portions for facilitating the entry of the material.

3. A material crusher in accordance with claim 1, the ribs on one of said plates progressively increasing in height toward their lower ends and terminating in reversely beveled lower end portions for facilitating the discharge of the material.

4. A material crusher in accordance with claim 1, the ribs progressively increasing in height from opposite ends of their respective plates toward the other ends of said respective plates and terminating in oppositely beveled end portions for facilitating the entry and discharge of the material.
